UNITED STATES PATENT OFFICE.

JONATHAN CHASE, OF BOSTON, MASSACHUSETTS.

COAL-ELEVATOR.

SPECIFICATION forming part of Letters Patent No. 399,835, dated March 19, 1889.

Application filed August 11, 1887. Renewed July 19, 1888. Serial No. 280,454. (No model.)

To all whom it may concern:

Be it known that I, JONATHAN CHASE, of Boston, county of Suffolk, and State of Massachusetts, have invented an Improvement in 5 Coal - Elevators, of which the following description, in connection with the accompanying drawings, is a specification, like letters on the drawings representing like parts.

This invention relates to barges or vessels especially adapted for the transportation of coal, sand, and other granular material, it having for its object to construct a barge or vessel, as will be described, whereby the cargo of coal, sand, or other granular material may 15 be rapidly discharged with substantially little labor.

In accordance with my invention the barge or vessel is provided with a false bottom having its center preferably composed of a number 20 of doors, each of which has a chain or rope or other suitable mechanism extended above the deck of the barge or vessel, where it is fastened in any suitable manner. The doors referred to are held normally closed by 25 the said chains or ropes, and when closed form an auxiliary chamber or pocket, in which is located, as herein shown, a screw conveyer adapted to be rotated by a stationary engine carried by the barge. The auxiliary chamber 30 or pocket referred to communicates with a second chamber or pocket, through which is revolved a series of buckets or scoops attached to an endless belt or apron passed about and revolved by a pulley on the shaft of the screw 35 conveyer, and a pulley on a shaft having bearings, as shown, in two stays or masts erected from the deck of the barge or vessel.

The particular features in which my invention consists will be pointed out in the claims 40 at the end of this specification.

Figure 1 is a longitudinal section of a barge or vessel constructed in accordance with my invention, the section being taken on the line $x-x$ of Fig. 2, the stationary engine being 45 shown in elevation. Fig. 2 is a section of Fig. 1 in line $y-y$; Figs. 3 and 4, details to be referred to; and Fig. 5, a sectional detail to be referred to, the section being taken on line $y'-y'$, Fig. 1. 50 The barge or vessel a , which may be of any usual or well-known construction, is provided,

as herein shown, with a false bottom composed, preferably, of oppositely-inclined parts, a' a'' , extended downward toward the center of the vessel, and having connected to or forming 55 part of them, as herein shown, a trough or channel, a^3 , (see Figs. 1 and 3) forming a chamber or pocket, a^4 , in which is located a screw conveyer, a^5 , the top or upper wall of the said chamber being composed of movable 60 sections, herein shown as doors b b' , hinged, as at b^2 , to the parts a' a'' . (See Fig. 3.)

Each door b b' has connected to it, as herein shown, a rope, rod, or chain, b^3 , extended to the deck and secured to a drum or roller, b^x , 65 on a shaft, b^4 , provided, as herein shown, with a hand-wheel, b^5 , and a brake mechanism, consisting, as shown, of a pinion, b^6 , and a pawl, b^7 .

The chamber or pocket a^4 communicates at 70 one end, as herein shown, with a second chamber or pocket, c , (see Figs. 1 and 2,) into which coal or other material is deposited by the screw conveyer a^5 .

The coal or other material in the vessel a , 75 which is supported above the false bottom, is admitted into the chamber a^4 by unwinding or releasing the ropes or chains b^3 , so as to permit the doors b b' to be opened by the weight of the coal or other material upon 80 them.

The doors b b' will be opened to admit such quantity of coal or other material into the chamber a^4 as will permit the screw conveyer to be operated. The coal thus admitted to 85 the chamber a^4 is carried forward by the screw conveyer and deposited in the auxiliary chamber or pocket c , the said screw conveyer being driven, as herein shown, by a belt, c' , passed about a pulley, c^2 , on the shaft c^3 of 90 the said screw conveyer, and about a pulley, c^4 , on the main shaft c^5 of a stationary engine, c^6 , herein shown as supported upon a platform, c^7 . The coal or other material deposited in the pocket c is taken out thereof, as 95 herein shown, by buckets or scoops d , secured to an endless belt or apron, d' , passed about a pulley, d^2 , on the shaft d^3 , and about a pulley, d^3 , on a shaft, d^4 , having bearings in two stays or masts, d^5 , herein shown as extended 100 below the deck of the vessel, and stepped, as at d^6 , in cross beams or braces d^7 .

The pulleys are herein shown as hexagonal in shape, to prevent slipping of the endless belt or apron, which is made to travel by the rotation of the screw-shaft c^3 .

- 5 The coal or other material carried upward by the buckets d may be discharged into a chute, d^9 , pivoted on a shaft, d^{10} , having bearings in the masts d^5 , the lowermost end of the said chute resting upon a staging or platform, 10 d^{12} , secured by suitable braces, d^{13} , to the said masts.
- The chute d^9 is provided with an opening, e , (see Fig. 4,) through which the endless chain of buckets travels, and at the sides of 15 the said opening are erected guards or shields e' , in which is supported the arbor e^2 of a gate or valve, e^3 , adapted to occupy the position shown in Fig. 2 when the chute is tipped into the position shown in the said figure, or to 20 stand upright in the position shown in Fig. 3 when the chute is tipped in the opposite direction to that shown in Fig. 2—that is, into the position shown in Fig. 3. With the chute d^9 in the position shown in Fig. 2 the coal or 25 other material falls from the buckets, and is discharged from the chute in the direction of arrow 20 into, it may be, a second chute—not shown, but which in practice may be supported from the wharf or another barge or 30 vessel lying on the port side of the barge, or from the barge itself.

- It may be desired to discharge the load on the starboard side of the barge, and in this case the chute d^9 will be turned on its pivot 35 by a man on the platform d^{12} , or in other manner, so as to occupy the position shown in Fig. 3. In this position the gate or valve e^3 is erect, and the coal discharged from the buckets falls beyond the said gates and slides 40 down the chute on each side of the shields e' , or in the direction of arrow 21.

I have herein described the doors $b b'$ as

extended the length of the barge or vessel; but instead thereof I may employ a number of small doors connected above the deck and 45 operated independently of each other, so that the amount of coal or other material admitted to the chamber a^4 may be increased as desired.

I do not desire to limit myself to the exact 50 mechanism shown for holding the doors in their closed position.

I claim—

1. A barge or vessel provided with a trough or channel, a^3 , extended longitudinally the 55 length of the said vessel and forming pockets a^4 and c , a metallic screw, a^5 , located in the trough a^4 , and having its shaft c^3 extended through the pocket c , an endless chain of buckets or scoops driven from the shaft c^3 , a 60 pivoted chute, d^9 , having an opening through which the endless chain of buckets passes, and means, substantially as described, to rotate the shaft c^3 , substantially as specified.

2. A barge or vessel provided with a trough 65 or channel, a^3 , extending lengthwise thereof, and having a chamber or pocket, c , a metallic screw, a^5 , located in the said trough, and having its shaft c^3 extended through the said chamber or pocket c , an endless chain of 70 buckets driven from the said shaft, a chute to receive the material discharged from the said buckets, hinged doors or sections $b b'$ to cover or partly cover the top of the said trough, and connections for operating said doors from 75 above, substantially as set forth.

In testimony whereof I have signed my name to this specification in the presence of two subscribing witnesses.

JONATHAN CHASE.
